UNITED STATES PATENT OFFICE.

GEORGE J. McCOY, OF FOSSIL, OREGON.

VEHICLE-REACH.

No. 857,822.

Specification of Letters Patent.

Patented June 25, 1907.

Application filed October 16, 1906. Serial No. 339,201.

To all whom it may concern:

Be it known that I, GEORGE J. McCOY, a citizen of the United States, residing at Fossil, in the county of Wheeler and State of Oregon, have invented certain new and useful Improvements in Vehicle - Reaches, of which the following is a specification.

This invention provides a reach or coupling for the front and rear axles of vehicle running gear which will have a certain amount of movement to adapt itself to the various movements and thereby obviate wrenching and abnormal strain on the bolts, braces and adjunctive parts.

For a full description of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a top plan view of a portion of a vehicle running gear embodying the invention. Fig. 2 is a vertical longitudinal section thereof. Fig. 3 is a detail view of a portion of the front axle and reach or coupling, showing the parts on a larger scale and having portions broken away to illustrate more clearly the relative arrangement of the parts.

Corresponding and like parts are referred to in the following description and indicated in all the views of the drawings by the same reference characters.

The running gear comprises front axle 1, rear axle 2, reach or coupling 3, hounds 4 and braces 5, the latter interposed between the hounds and the rear portion of the reach.

The hounds are clipped at their rear ends 45 to the axle 2 and their front ends extend along opposite sides of the reach and are bolted or otherwise firmly connected thereto. The rear end of the reach or coupling 3 is rigidly connected to the axle in any substantial way, as by means of a clip 6 which embraces the axle and the upper and lower sides of the rear portion of the coupling to which it is bolted or otherwise secured.

The coupling or reach 3 is hollow, being 55 preferably a length of pipe. The front end of the reach is connected with the bolster by

means of a swivel joint, thereby admitting of movement of said axle without wrenching or straining the fastenings, braces, etc. As illustrated, the joint comprises a plate 7 provided with a stem 8, the latter entering the front end of the reach or coupling and said plate being folded or similarly fastened to the bolster 9 placed upon the axle 1.

A nut or collar 10 is fitted to the front end 65 of the coupling and serves to strengthen the same and to provide an extended bearing for abutting against the plate 7 of the member forming the swivel joint between the front bolster 9 and the coupling. A collar 11 is 70 provided upon the reach or coupling a short distance from its front end and constitutes a stop to sustain the pulling strain and prevent separation of the front and rear axles. Collars 12 and 13 are loose upon the reach and 75 are located in the rear of the fixed collar 11. An upper rod or bar 14 connects the upper portion of the collar 12 with the axle at a point above the springs 15. A second rod or bar 16 connects the lower portion of the 80 collar 12 with the axle at a point below the bolster. A king bolt 17 passes through the front ends of the parts 14 and 16. The connections 14 and 16 may be welded or otherwise attached to the collar 12 and are arranged one above and the other below the reach and serve to sustain the draft when the vehicle is drawn over the road. A brace 18 connects the lower portion of the collar 13 with the axle. The king bolt 17 passes 90 through the ends of the several connecting rods or bars 14, 16 and 18. The fifth wheel 19 passes through a loop or coupling 20 applied to the lower side of the rod or bar 16.

From the foregoing it will be understood 95 that the front end of the reach or coupling 3 is connected with the front axle by a swivel joint, hence is adapted to turn with reference to the axle so as to obviate torsional strain and thereby prevent wrenching and straining of the fastenings, braces and the like and resulting in materially prolonging the period of usefulness of the running gear.

Having thus described the invention, what is claimed as new is:

1. In a vehicle running gear, the combination of front and rear axles, a reach having rigid connection at its rear end with the rear axle, a plate having connection with the front axle and provided with a stem fitted loosely 110 within the front end of the reach, a fixed stop near the front end of the reach, collars

loose upon the reach in the rear of said fixed stop, and connecting means between said collars and the front portion of the running gear.

5 2. In vehicle running gear, the combination of front and rear axles, a tubular reach having rigid connection with the rear axle and provided near its front end with a rigid stop and having its front end reinforced, a 10 plate attached to the rear side of the bolster fitted upon the front axle, and provided with a stem fitted loosely within the reinforced end of the reach, a loose collar 12 mounted upon the reach in the rear of the fixed stop, 15 connections 14 and 16 between the upper and lower portions of the loose collar and the front portion of the running gear, the con-

nexion 16 having a loop or keeper to receive the fifth wheel, a loose collar 13 likewise mounted upon the reach in the rear of the fixed stop and loose collar 12, and a connection 18 between the lower portion of the loose collar 13 and the front portion of the running gear and extending below the front axle, the several connections 14, 16 and 18 having 25 king bolt connection with the front portion of the running gear.

In testimony whereof I affix my signature in presence of two witnesses.

GEORGE J. McCOY. [L. S.]
